UNITED STATES PATENT OFFICE.

ELEAZER KEMPSHALL, OF BOSTON, MASSACHUSETTS, ASSIGNOR TO THE KEMPSHALL MANUFACTURING COMPANY, A CORPORATION OF NEW JERSEY.

PLAYING-BALL.

SPECIFICATION forming part of Letters Patent No. 700,942, dated May 27, 1902.

Application filed April 9, 1902. Serial No. 102,029. (No model.)

To all whom it may concern:

Be it known that I, ELEAZER KEMPSHALL, a citizen of the United States, residing in Boston, in the county of Suffolk and State of Massachusetts, have invented certain new and useful Improvements in Playing-Balls, of which the following is a specification.

This invention relates to playing-balls, and especially to those used in the game of golf; and its principal object is to increase the resiliency and flying power of the ball.

In the drawings forming part of this specification, Figure 1 is a part-sectional view of a playing-ball made in accordance with my present improvements. Fig. 2 illustrates, partly in section, a core formed of rubber threads or strips and used in making my improved ball. Fig. 3 is an enlarged sectional detail illustrating one way of cutting the threads or strips which form the core. Fig. 4 is a sectional view illustrating the manner of forming a shell upon the core.

Upon a center piece 3, preferably of gutta-percha, I wind at high tension threads or strips *a* of soft rubber to form a spherical body or core 1, the threads or strips being wound continuously in different directions. Said core I inclose in segments 6 and 7 of gutta-percha and weld the latter together when heated in suitable dies 8 and 9, the complete shell being indicated at 5, Figs. 1 and 3. The dies are preferably provided with pits 10, so as to form brambles upon the shell, as at *c*. The pressure of the dies upon the balls is

maintained until the shell cools and hardens. After removing the ball from the dies I form one or more holes *d* in the shell, into each of which I introduce a sharp blade or instrument *e* to sever some or all of the windings of tensioned rubber, as indicated at *g*, Fig. 3. Preferably the severing process is carried to an extent to substantially release all of the threads, as illustrated at Fig. 1, in which the playing-ball is indicated by the letter *A*. The holes I close by plugs, as at *m m*, Fig. 1.

It will be understood that when winding the rubber threads they are highly attenuated by reason of the tension put thereon, and hence they pack closely together throughout the core 1, and more layers are required in mak-

ing said core than would be required for a core of equal diameter and having the threads wound in an untensioned condition. It will also be understood that when the threads are cut, as already explained, they are released and tend to recover their normal condition—that is, to shorten and thicken—and if the threads were unrestrained by the shell 5 they would swell and form a ball of very large diameter. Said expansive action, however, is restrained by the shell, and the imprisoned tense rubber exerts upon the shell a powerful and substantially uniform expansive tendency. Because of this condition of the core it tends to maintain the true spherical form of the shell, and it results that when the shell becomes distorted by a blow it recovers its original form instantly, and hence the ball springs from the club with phenomenal speed. Moreover, because of the compressed condition of the severed rubber threads they resist further compression from the club, and hence the liveliness of the ball is augmented. The energy stored up in the threads when they are wound under tension to form the core instead of being exerted, as heretofore, to compress the core is transformed into expansive energy, which tends powerfully to expand the shell, and hence greatly improve the playing qualities of the ball.

The process of making my improved playing-ball forms the subject-matter of my other pending application, filed April 14, 1902, Serial No. 102,804.

Having described my invention, I claim—

1. A playing-ball comprising a core and a shell thereon; said core consisting of a mass of bits of rubber and being held under compression by said shell.

2. A playing-ball comprising a core and a shell of plastic material thereon; said core consisting of a mass of severed rubber threads or strips held under compression by said shell.

3. A playing-ball comprising a shell and a core; the latter consisting of windings or layers of tensioned rubber threads, and at least a considerable portion of said windings being severed, so that at least a large part of the threads are released and exert a constant expansive pressure upon said shell.

4. A playing-ball comprising a shell of plastic material and a core; the latter consisting of a mass of fragments of rubber threads, whose tendency is to shorten and thicken, said tendency being resisted by said shell.
5. A playing-ball comprising a shell and a core; the latter consisting of a mass of fragments of rubber threads or strips, the ends of said fragments being unsecured, and said fragments exerting pressure upon said shell.
6. A playing-ball comprising a shell and a core; the latter consisting of windings or layers of tensioned rubber threads; said core being mutilated at different points, and many or all of the rubber threads being released by reason of said mutilation and tending constantly to expand said shell.
7. A playing-ball comprising a gutta-percha shell and a core; the latter consisting of windings or layers of tensioned rubber threads; said shell and core being mutilated at different points, and the rubber threads being released by reason of said mutilation, and tending constantly to expand said shell.
8. A playing-ball comprising a shell and a core; the latter consisting of windings or layers of tensioned rubber threads, and at least a portion of said windings being severed, whereby at least some of the threads are released and exert a constant expansive pressure upon said shell; and the latter having closed apertures.
9. A playing-ball comprising a shell which consists of welded segments of plastic material, and a core; the latter consisting of windings or layers of tensioned rubber threads, and at least a portion of said windings being severed, whereby at least a portion of the threads are released and exert a constant expansive pressure upon said shell.
